LOG REFLOATING APPARATUS

John Albert Ellis, St. Louis de Courville, Quebec,
Canada

Application July 9, 1932, Serial No. 621,636, and
in Canada June 27, 1932

3 Claims. (Cl. 214—1)

This invention relates to log refloating apparatus and it is designed particularly for loosening the pulp wood from jams forming in storage ponds. In jams around the edges and in the relatively shallow parts of mill storage ponds the wood rests on the bottom and sometimes becomes piled up as high as twenty-five feet. The usual way of loosening these jams, which consists in employing men with pike poles, is extremely difficult and dangerous, besides involving very high labour costs.

The arrangement, according to this invention, has been designed to loosen pulp wood jams in the minimum of time and with the minimum of expense. The apparatus consists essentially in a floating body in the storage pond connected by cables to two fixed anchors and having mechanism on it for winding up one or another of these cables to draw it towards or away from a jam of logs. Mounted on the body is a boom having a grappling hook at its free end and a cable controlling its raising and lowering. The apparatus is operated by advancing the body towards the mass of logs, permitting the grappling hook to drop into engagement with the mass and then withdrawing the body from the mass, thus loosening the jam.

The invention may be more clearly understood by reference to the attached drawing in which Fig. 1 is a view indicating the operation of the apparatus;

Fig. 2 is a partly sectional longitudinal elevation of the floating body forming the essential part of the apparatus, and

Fig. 3 is a front elevation of the grappling hook.

The floating body A has mounted on it an engine 1 and cable winding drums 2, 3 and 4 while levers 5 are provided for the selective control of the mechanism for connecting these drums to the engine. On drum 2 is wound one end of a cable 6, the other end of which is connected to an anchor 7 fixed on land. A cable 8 is wound on drum 3 and connected to an anchor 9 in a similar way. To allow easier movement of the cables 6 and 8 they run over pairs of rollers 10 and 11 respectively at either end of the body A.

Mounted at the front of the floating body is a boom 12 which may be single or double, the two parts in the latter case being connected to each other by cross-stays. The boom is pivoted at 13 about a horizontal axis for movement in a vertical plane, and it may, of course, be so pivoted as to permit it to swing sideways also. Connected to the free end of the boom is a grap-

pling hook 14 which is preferably of the form shown in Fig. 3, where it is provided with two prongs 15 and 16 connected to each other on one side by a plate 17 and on the other side by a bar 18.

The raising and lowering of the boom is controlled by a cable 19 passing over a pulley 20 and having one end fixed at 21 to a standard 22 on the floating body and having its other end wound on the drum 4. Two connections, arranged in the manner indicated in Fig. 3, are provided between the pulley 20 and grappling hook 14.

In operating the device the drum 2 is first connected to the engine 1 to wind up the cable 6 and cause the body A to approach the mass or jam of logs B. When the body has sufficiently approached the mass the cable 19 will be unwound from the drum 4 to allow the boom 12 to drop and the grappling hook 14 to engage with the logs of the mass, the hook usually being directed to a suitable place for engagement by a man on the jam. When the hook is engaged with the mass the drum 3 is caused to wind up the cable 8, the cable 6 being allowed of course to unwind during this time, and the body is thus drawn away from the mass and the jam loosened through the action of the grappling hook.

It will be seen that with the arrangement described the body in all its actions is moved without slip, that is, its movement corresponding to one turn of its engine is the same whether it is free or under load. The term "without slip" serves therefore to bring out the fact that the power source does not work only against water as would be the case were the floating body provided with a paddle wheel or the like.

The apparatus of my invention may be very easily and cheaply constructed. Its use is safe and, when run by two men, one on the floating body and the other on the log jam, it will do in unit time the work done by from ten to fourteen men using pike poles.

Various modifications may be made in the invention without departing from the spirit thereof or the scope of the claims and, therefore, the exact forms shown are to be taken as illustrative only and not in a limiting sense, and I desire that only such limitations shall be placed thereon as are imposed by the prior art or are specifically set forth in the appended claims.

What I claim as my invention is:

1. In a device for refloating logs from a log jam in a body of water, a float, means for positively moving said float up to and away from said

2

log jam, a boom pivoted at one end to said float, a hook member carried at the free end of said boom, means independent of said float operating means for raising the free end of said boom out of engagement with the logs in said jam while said float is moved up to the latter and for then lowering said boom to engage said hook with said logs whereby subsequent movement of said float away from said jam will result in said hook refloating logs from said jam.

2. In a device for refloating logs from a pile thereof, a pair of spaced anchors, a float, cables connecting said float to said anchors, drum means for taking up and paying out said cables to move said float up to and away from said pile of logs, a boom pivoted at one end to said float, a grappling hook mounted at the free end of said boom, means for raising and lowering the free end of said boom independently of the movement of said float whereby said end may be raised to clear said pile of logs when said float is moved up to the same and then lowered to engage the logs in said pile, said float being then backed

away from said pile through operation of said drum means to disengage the logs engaged by said hook from said pile.

3. In an apparatus for refloating pulp wood logs from a mass thereof jammed in a mill pond, a float disposed in said pond, anchors disposed on opposite sides of said pond, cables connecting said float to said anchors, drum means on said float for taking up and paying out said cables to move said float up to and away from said mass of logs, a boom pivoted at one end to said float, and having a log engaging hook mounted at the free end thereof, means independent of said float operating means for raising the free end of said boom to clear said logs as said float is moved up to said mass and for then lowering said boom to permit said hook to be engaged with logs on said mass whereby subsequent movement of said float away from said mass of logs will result in refloating logs from said mass in the wake of said float.

JOHN ALBERT ELLIS.
